CLAIM

I claim the ornamental design for a laminating cartridge, as shown and described.

DESCRIPTION

FIG. 1 is a front perspective view of a laminating cartridge embodying the present invention.

FIG. 2 is a detail view of a portion of the laminating cartridge of FIG. 1.

FIG. 3 is an alternate perspective detail view of the portion of the laminating cartridge of FIG. 2.

FIG. 4 is a front view of the laminating cartridge of FIG. 1.

FIG. 5 is a rear view of the laminating cartridge of FIG. 1.

FIG. 6 is right side view of the laminating cartridge of FIG. 1.

FIG. 7 is a left side view of the laminating cartridge of FIG. 1.

FIG. 8 is a top view of the laminating cartridge of FIG. 1; and,

FIG. 9 is a bottom view of the laminating cartridge of FIG. 1.

The broken lines illustrate environment and form no part of the claimed design. Further, the left side portion detailed in FIGS. 2 and 3 is mirrored on the right side portion of the laminating cartridge.
